UNITED STATES PATENT OFFICE

2,146,192

ANIMATED DISPLAY

Chester H. Kraemer, Scranton, Pa., assignor to
 General Outdoor Advertising Co., Chicago, Ill.,
 a corporation of New Jersey

Application October 24, 1938, Serial No. 236,632

12 Claims. (Cl. 40—34)

My invention relates to animated advertising displays, and especially to a type of sign intended for outdoor advertising, but capable also of being built on a much smaller scale for use as an animated window display. More particularly, my invention consists of an animated display adapted to create an illusion of pouring liquids from one container into another container.

10 The mechanism which I have chosen to illustrate my invention is adapted to operate a sign which creates the illusion of a liquid pouring from a bottle into a glass. The mechanism consists of two cams simultaneously rotating 15 with a motor driven display member bearing a representation of a moving liquid upon its face. These two cams are adapted to impart an oscillatory motion to two other display members, which reproduce, respectively, the motion of a hand tilting a bottle, and a glass being filled 20 with liquid and foam. I recognize that the use of cam-operated display members, simulating moving figures, animals, or vehicles, is old, and that many interesting but rather complex 25 methods have been devised for simulating flowing liquids. However, to the best of my knowledge, the use of a rotating display member simulating the transfer of a liquid from a second display member to a third display member, said first member mechanically actuating the two 30 oscillating members, is new.

Accordingly, one of the objects of my invention is the production of an animated display simulating the transfer of fluid from one container to another.

Another object of my invention is the production of an animated display of the class described in which a continuously rotating display member creates an illusion of liquid transfer between two oscillating display members, each mechanically actuated by said first display member.

Another object of my invention is the production of an animated outdoor advertising display whose mechanical construction is of the simple, rugged, and efficient nature demanded by this type of service.

Other objects and advantages of my invention will become apparent from a consideration of the following specification, read in conjunction with the accompanying drawings, in which:

Fig. 1 is a front elevation of the invention, showing the bottle in a raised position subsequent to pouring;

Fig. 2 is a front elevation of the invention, showing the bottle lowered, while pouring;

Fig. 3 is a rear elevation of the invention, showing the position of the mechanism while the bottle is in the pouring position;

Fig. 4 is a sectional view, taken along the lines 4—4 of Fig. 3;

Fig. 5 is a sectional view, taken along the lines 5—5 of Fig. 3; and

Fig. 6 is a detailed sectional view, taken along the lines 6—6 of Fig. 3.

In all of the figures, like reference numerals refer to like parts.

The mechanism of the sign is mounted upon a heavy framework, shown in part at 10. A large 15 stationary display board 11 provides additional support for the mechanism and serves as an attractive background for the display members. The display board 11 may be braced against the buffeting of the winds by means of braces 14. 20 Directly behind board 11 is mounted a rotating display member 16 comprising a framework made up of radial spokes 17 emanating from gusset plate 15 and rim pieces 18, covered with and stiffened by means of an annular strip 19 of display board, or other material such as sheet iron or Masonite. The rotating display member turns upon a shaft 20 passing through gusset plate 15, and pivoted in a socket 21 mounted on display board 11 and supported by journal 22 25 mounted on the supporting framework 10. The rotating display member 16 has painted or printed upon it a representation of flowing liquid extending through a semicircle, as indicated at 23, in a position behind a slot 12 in the display board 11. The outline of this slot is that of a stream of liquid pouring from a bottle 25 held in a down-tilted position, into a glass 30. Accordingly, liquid will appear to be flowing during 30 that half of a revolution of the display member 16 during which the representation of the pouring liquid 23 is moving past and behind slot 12.

The spokes 17 of display member 16 carry two cams 35 and 36, which are spacedly supported at a slight distance from the spokes 17 by means 45 of spacing rods 31. These cams 35 and 36 may be conveniently formed out of channel members, which guide the rollers 40 of follower members 38 and 39, respectively. A cross section of the channel and roller construction is given in Fig. 6. 50 The cams are usually formed by running the channel through a suitable bending machine, and after the desired contour has been reached, joining the ends of the channel member to produce the continuous cam. Although I have 55

shown the contour of my cams in the drawings, I wish it to be understood that this contour may be adjusted to bring about the most realistic illusion of pouring when the sign is viewed from a distance. The ability to alter the shape of the cams allows some scope for the exercise of artistic ingenuity on the part of the artist designing the display.

The glass 30, and the hand 31 are an integral panel structure of wood, Masonite or similar material, painted to represent a human hand holding a glass. It is to be noted, however, that the edges of the glass only are reproduced; thus giving the appearance of transparent glass, behind which the flowing liquid is visible. The appearance of liquid filling the glass is created by a moving display member 32, painted to resemble liquid in a glass, with foam floating on top of the liquid. This display member is vertically oscillated by an arm 33 attached to the cam follower 39, which is pivoted to display board 11 by means of pivot 34. Follower 39 bears a roller 40 engaging the cam 36 and is oscillated thereby. It is desirable that follower 39 be of a balanced construction, in order to impose as small a load on cam 36 as possible. When cam 36 rotates with display member 16, an oscillating motion is imparted to display member 32, producing the impression of liquid rising and falling in glass 30. The motion of the liquid simulating member 32 is naturally coordinated with the tilting of bottle 25, as will be described later.

The display member 25 consisting of a bottle and a human hand holding the bottle are an integral panel structure, having the details of bottle and hand suitably painted or printed thereon. The display member 25 is pivoted upon the end of a shaft 26 journaled through display board 11. The shaft 26 is given an oscillating movement by means of counterbalanced crank 27, pivoted thereupon, and actuated by cam follower 38, linked to crank 27 by means of pin 28 and slidably supported upon shaft 20 by means of fork 29. Follower 38 bears a roller 40 actuated by cam 35 as previously described. The shape of cam 35 is such as to give a tilting motion to display member 25, simulating the motion of a hand tilting a bottle. Power for operating the sign may be obtained from an electric motor 5 connected to shaft 20 through two chain and sprocket speed reduction drives 7 and 9.

The operation of the sign is as follows. Display member 16 rotates continuously. At the time that the last of the flowing fluid representation 23 passes the slot 12, the bottle and hand 25 tilt upwardly, thus making the flow of liquid seem to cease because of the upward tilting of the bottle. At the same time, the liquid level indicating member 32 in glass 30 quickly moves down, out of sight behind hand 31. After rotating display member 16 has turned through approximately a half revolution, bottle 25 again moves down in a pouring position, the liquid representation 23 rotates past slot 12, producing an illusion of liquid pouring into glass 30. At the same time, the liquid level indicating display member 32 rises in glass 30, simulating the filling of the glass with liquid being poured from the bottle. The described operations are then repeated. A complete cycle of operation occurs at every revolution of display member 16.

Although I have described an embodiment of my invention in which the pouring of liquid from a bottle into a glass is simulated, I wish it to

be understood that many modifications of my invention are possible without departing from the spirit of the invention. Liquids other than foaming liquids may be simulated, and liquids may be poured from other containers than bottles into other containers than glasses. My invention is not restricted to simulating pouring liquids, as comminuted, granular, or powdered material, such as crystal salt, may be depicted.

What I desire to protect by United States Letters Patent and what I claim is:

1. An animated display comprising an oscillating display member, a second oscillating display member, and a rotating display member simulating the transfer of liquid from the first display member to the second display member.

2. An animated display comprising an oscillating display member simulating a liquid dispensing container, a simulated receptacle, a second oscillating display member simulating liquid in said receptacle, and a rotating display member simulating liquid flowing from the dispensing container to the receptacle.

3. An animated display comprising an oscillating display member simulating a liquid dispensing container, a simulated receptacle, a second oscillating display member simulating liquid in said receptacle, and a rotating display member simulating liquid flowing from the dispensing container to the receptacle, and means actuated by said rotating display member for actuating the aforesaid oscillating display members.

4. An animated display comprising a fixed display board, a slot therein, a rotating display member behind said slot simulating the appearance of liquid flowing past the slot, an oscillating display member simulating a liquid dispensing display member operated by said rotating display member, a simulated receptacle, and a second oscillating display member simulating liquid filling said receptacle operated by said rotating display member.

5. An animated display for simulating the effect of liquid filling a receptacle, therefor, comprising a simulated receptacle, an oscillating liquid simulating display member located in such a position relative to said receptacle as will tend to make said display member appear to be within said receptacle, and means for oscillating said liquid simulating member.

6. An animated display for simulating the effect of liquid filling a receptacle, therefor, comprising a simulated receptacle, an oscillating liquid simulating display member located in such a position relative to said receptacle as will tend to make said display member appear to be within said receptacle, a rotating display member simulating a stream of liquid flowing into said receptacle, and means operated by said rotating display member for actuating the aforesaid oscillating display member.

7. An animated display for simulating the effect of liquid filling a receptacle, therefor, comprising a simulated receptacle, an oscillating liquid simulating display member located in such a position relative to said receptacle as will tend to make said display member appear to be within said receptacle, and a rotating display member simulating a stream of liquid flowing into said receptacle.

8. An animated display for simulating the effect of liquid filling a receptacle, therefor, comprising a simulated receptacle, an oscillating liquid simulating display member located in such a position relative to said receptacle as will tend

to make said display member appear to be within said receptacle, a slot therein having the configuration of a stream of liquid, and a rotating display member revolving behind said slot for simulating the appearance of liquid issuing from the container and flowing past the slot in a stream having the configuration of said slot.

9. An animated display for simulating the effect of a stream of liquid issuing from a container, comprising an oscillating display member for simulating the effect of a container being tilted for pouring, and a rotating display member behind said container for giving an illusion of liquid pouring from the mouth of said container.

10. An animated display for simulating the effect of a stream of liquid issuing from a container comprising a fixed display board, a slot therein having the configuration of a stream of liquid, an oscillating display member for simulating the effect of a container being tilted for pouring, a rotating display member revolving behind said slot for simulating the appearance of liquid issuing from the container and flowing past the slot in a stream having the configuration of said slot.

11. An animated display comprising a fixed display board, a slot therein, a rotating display member bearing upon a fraction of its face a representation behind said slot simulating the appearance of liquid flowing past the slot, an

oscillating display member simulating a liquid dispensing display member, a simulated receptacle, a second oscillating display member simulating liquid filling said receptacle, cam means operated by said rotating display member for 5 tilting said first oscillating display member during the period when the liquid representation is passing behind the aforementioned slot, and other cam means operated by said rotating display member for actuating the second oscillating display member in appropriate relationship to the movement of said liquid representation past said slot.

12. An animated display for simulating the effect of a stream of liquid issuing from a container comprising a fixed display board, a slot therein having the configuration of a stream of liquid, an oscillating display member for simulating the effect of a container being tilted for pouring, a rotating display member bearing upon 15 a fraction of its face a representation revolving behind said slot for simulating the appearance of liquid issuing from the container and flowing past the slot in a stream having the configuration of said slot, and cam means operated by said 20 rotating display member for tilting said oscillating display member during the period when the liquid representation is passing behind the aforementioned slot.
